UNITED STATES PATENT OFFICE.

WEBSTER O. NELSON, OF VICTOR, IOWA.

DESIGN FOR A RAILWAY SPLICE-BAR.

SPECIFICATION forming part of Design No. 29,892, dated December 27, 1898.

Application filed November 1, 1898. Serial No. 695,243. Term of patent 14 years.

To all whom it may concern:

Be it known that I, WEBSTER O. NELSON, a citizen of the United States, residing at Victor, in the county of Iowa and State of Iowa, have invented and produced a new and original Design for a Railway Splice-Bar, of which the following is a specification, reference being had to the accompanying drawings, forming part thereof.

10 Figure 1 is a perspective of my splice-bar, and Fig. 2 is a transverse sectional view thereof, and jointly considered they clearly show the contour of the bar and its novel features relative to the art to which my invention pertains.

15 The letter A designates the solid body portion provided with a plurality of transverse bolt-holes in a line that is midway between its top and bottom.

20 B is a flat top face extending from end to end.

C is a concave on the inner flat face D of the body A, that extends from end to end of the body.

F is the broad flat bottom, and H is the 25 front flat face extending down from the flat top face to a flange J, that has an inclined top face and is provided with a plurality of notches in its outer edge.

Having described my invention and pointed 30 out the novel features in the configuration thereof relative to the art to which it pertains, what I claim as new, and desire to secure by Letters Patent therefor, is—

35 The design for a railway splice-bar, as herein shown and described.

WEBSTER O. NELSON.
